Attest,

UNITED STATES PATENT OFFICE.

OTTO A. HOKANSON, OF WOODSTOCK, ILLINOIS, ASSIGNOR TO WOODSTOCK TYPE-
WRITER COMPANY, OF WOODSTOCK, ILLINOIS, A CORPORATION OF ILLINOIS.

TYPEWRITER.

Application filed December 14, 1923. Serial No. 630,584.

To all whom it may concern:

Be it known that I, OTTO A. HOKANSON, a citizen of the United States, residing at Woodstock, in the county of McHenry and 5 State of Illinois, have invented certain new and useful Improvements in Typewriters, of which the following is a specification.

This invention relates to a typewriting machine in which the parts are foldable 10 relative to one another to bring them into compact relation for transportation, and has for its object the provision of such a machine which shall be of improved construction and operation and in which the platen 15 carriage may be mounted on a folding part and operated by a power device mounted on a different portion of the machine.

The invention is exemplified in the combination and arrangement of parts shown in 20 the accompanying drawings and described in the following specification, and it is more particularly pointed out in the appended claims.

In the drawings,—

25 Fig. 1 is a fragmentary vertical sectional view of one form of typewriting machine embodying the present invention.

Fig. 2 is a fragmentary top plan view with parts in section showing the mechanism illustrated in Fig. 1.

30 Fig. 3 is a detail sectional view on line 3—3 of Fig. 1.

Figs. 4 and 5 are elevations of the bracket by which the operating part is attached to 35 the carriage.

In the form of typewriter illustrated in the drawings the numeral 10 designates a main base frame having the usual key levers 11 mounted thereon and having sublevers 12 40 connected by links 13 to the typebars 14 pivotally mounted on a typebar segment 15 supported on the main base frame. The main base frame may comprise an inner skeleton frame plate 16 at the side of the machine and an outer sheet metal frame 17.

45 These frame members are attached to one another and spaced apart by suitable spacing blocks 18, and the top edge of the outer frame member 17 is bent inwardly to 50 form a finishing flange 19, as shown in Figs. 2 and 3. A pivot bolt 20 extends through the two frame members 16 and 17 at the top of the base frame about midway of the machine and forms a pivotal support for a 55 folding arm 21, which carries the platen

bed 22. A similar pivot and arm is provided at the opposite side of the machine for the opposite end of the platen bed. The carriage 23 is slidably mounted on ways 24 supported on the platen bed 22, and ball 60 bearings 25 are preferably provided to facilitate easy movement of the carriage. A rack 26 is attached to the carriage 23 and meshes with a pinion 27 carried by a stud shaft 28 journaled in the carriage bed. The 65 lower end of the stud shaft 28 supports an escapement wheel 29 controlled by any suitable escapement mechanism, not shown. A bracket 30, shown in Figs. 1, 4 and 5, is attached to the rear of the carriage 23 and 70 is provided with a slot 31 for receiving a carriage propelling cord 32. The end of the cord 32 is provided with a ball or nut 33 for retaining the cord in the slot 31. Adjacent the end of the carriage bed a 75 bracket 34 is struck downwardly and supports a pulley 35 journaled thereon. The cord 32 passes around the pulley 35 and thence backwardly adjacent the side of the folding arm 21 to a pulley 36 journaled on 80 a bracket 37 struck inwardly from the frame member 16. From the pulley 30 the cord 32 passes downwardly to a spring drum 38 supported by the frame member 16. The spring drum 38 may be of any well known 85 and approved construction and is preferably provided with a double pawl 39 by which the tension of the spring on the cord 32 may be regulated. The inner end of the pivot bolt 20 is provided with a circumferentially 90 grooved stud or fair leader 40, about which the cord 32 passes as shown in broken lines in Fig. 1 when the platen carriage is moved to its folded position. When the platen carriage is returned to its operating position 95 the cord 32 will automatically return to the groove in the pulley 30 to operate the carriage under control of the escapement mechanism. It will be seen that in this way it is possible to mount the drum on the side of 100 the main frame where it will not interfere with the parts carried on the platen carriage support. The connection between the drum and the carriage is unbroken during the folding operation so that the carriage is 105 always operatively connected with the drum irrespective of the position of the carriage support. Passing the cord about a guide adjacent the pivot of the folding support makes it possible to use a non-separable con- 110

nection between the carriage and drum while the drum is mounted on a stationary portion of the frame and the carriage is foldable.

5 I claim:

1. In a compactible typewriter, a pair of frame members movable relative to one another, a platen carriage mounted on one of said members, an actuator for said platen carriage mounted on the other of said members, and a non-separable connection for operating said platen carriage from said actuator.

10 2. A typewriter comprising a main frame, a platen carriage frame mounted on said main frame and movable from an operative to an inoperative position thereon, a platen carriage movably mounted on said platen carriage frame, an actuator mounted on said main frame, and a device for connecting said platen carriage to said actuator, said device remaining intact during and following operation of said platen carriage frame.

15 3. A typewriter comprising a pair of frame members pivotally connected to one another, a platen carriage movably mounted on one of said frame members, an actuator for the platen carriage mounted on the other of said frame members, a flexible device connecting said platen carriage and actuator, and a guide for said flexible device mounted adjacent the pivotal connection between said frame members.

20 4. A typewriter comprising a main base frame, a platen carriage frame, an arm pivoted on said main base frame about midway fore and aft of said frame and supporting said platen carriage frame at the free end thereof, a platen carriage mounted to travel on said platen carriage frame, an actuator for said platen mounted on said main base frame, a flexible member connecting said platen carriage and actuator, and a guide for said flexible member adjacent the pivotal connection of said arm and main base frame.

25 5. A typewriter comprising a main frame, a platen carriage frame pivotally mounted on said main frame to move from an operative to an inoperative position, a platen carriage on said platen carriage frame, escape-
50 ment mechanism for controlling said platen carriage, a spring actuator mounted on said main frame for moving said platen carriage, and means for connecting said spring actuator and platen carriage at all positions of said platen carriage frame relative to said main frame.

60 6. In a folding typewriter, a main frame, a platen carriage frame pivotally mounted on said main frame, a platen carriage movable on said platen carriage frame, a spring drum mounted on said main frame, a flexible member connecting said spring drum and platen carriage, and a pulley on said main frame adjacent the pivotal connection be-

tween said main frame and said platen carriage frame for guiding said flexible connection to permit folding of said platen carriage frame while maintaining operative connection between said platen carriage and drum.

7. In a folding typewriter, a main frame having a side frame member, a drum mounted on said side frame member, an arm pivoted on said side frame member, a platen carriage frame mounted on said arm, a platen carriage mounted to travel on said platen carriage frame, a flexible connection between said drum and platen carriage, a pulley adjacent the pivotal connection between said main frame and platen carriage frame for guiding said flexible connection, and a second pulley mounted on said platen carriage frame adjacent the path of movement of said platen carriage for guiding said flexible connection.

10 8. In a typewriting machine, a pair of pivotally connected frame members, an actuator on one of said frame members, a device to be operated by said actuator on the other of said frame members, a flexible connection between said actuator and operated device, and a guide for said flexible connection about which said flexible connection is bent during folding movement of said frame members relative to one another.

9. A folding typewriter comprising a base frame, a platen carriage frame, a pivotal connection between said base frame and platen carriage frame, an actuating device on said base frame, an actuated device on said platen carriage frame, a flexible connection between said actuated and actuating devices, and a guide carried by said base frame concentric with said pivotal connection about which said flexible connection is folded during relative folding movement of said base frame and platen carriage frame.

10 10. In a typewriter, a pair of pivotally connected frame members, a flexible connector from one of said frame members to the other, and a pair of guides for said flexible connector positioned adjacent the pivotal connection between said frame members.

11. In a typewriter, a pair of pivotally connected frame members, a flexible connector extending from one of said frame members to the other, and a pair of guides for said flexible connector adjacent the pivotal connection between said frame members and arranged to alternately receive said flexible connector as said frame members are folded relative to one another.

12. In a typewriting machine, a base frame, a platen carriage frame pivotally mounted on said base frame, a flexible connector extending between said base frame and platen carriage frame, a guide pulley mounted on said base frame adjacent the pivotal connection between said base frame and

platen carriage frame and arranged to receive said flexible connector for one position of said platen carriage frame, and a second guide member adjacent said guide pulley for receiving said flexible connector when said platen carriage frame is folded to a different position on said base frame.

13. In a typewriter, a base frame having a vertical side wall, a spring drum mounted flatwise adjacent the face of said side wall, a foldable frame member pivotally mounted on said side wall, a platen carriage movable on said frame member, a flexible connection extending from said spring drum to said 10 platen carriage, and a guide adjacent the pivotal connection between said side wall and pivoted frame member for retaining said flexible connection in operative position during folding movement of said platen carriage frame.

14. In a typewriting machine, a frame having an upright side wall provided with spaced frame plates, a pivot bolt connecting said frame plates, an arm pivotally mounted on said pivot bolt, a guide pulley carried by one of said spaced frame members, a guide mounted on said pivot bolt, and a flexible member passing between said 25 guide pulley and said last mentioned guide and movable from one to the other when said pivot member is rotated on said pivot bolt.

15. A typewriting machine comprising a main frame, a platen carriage frame pivotally mounted on said main frame, a platen carriage movable on said platen carriage frame, a spring drum mounted on said main frame, a flexible member secured to said drum at one end and attached to said platen carriage at its other end, a pulley on said 30 platen carriage frame arranged adjacent one end thereof and about which said flexible member is guided, and a guide for said flex-

ible member adjacent the pivotal connection between said main frame and platen carriage frame for retaining said flexible member adjacent said pivotal connection for all 45 positions of said platen carriage frame.

16. In a typewriting machine, a pair of pivotally connected frame members, a flexible connector extending from one of said frame members to the other, and a pair of guides adjacent the pivotal connection between said frame members for retaining said flexible connector adjacent said pivotal connection irrespective of the position of said 50 frame members relative to one another.

17. In a typewriting machine, a main frame, a platen carriage frame pivotally mounted on said main frame, a platen carriage mounted to travel on said platen carriage frame, a bracket on said platen carriage, a guide pulley on said platen carriage frame adjacent one end thereof, a guide pulley on said main frame adjacent the pivotal connection between said main frame and platen carriage frame, a second guide adjacent said last mentioned guide pulley, a spring drum mounted on said main frame, and a flexible connector secured to the bracket on said platen carriage and passing over 60 the guide pulley on said platen carriage frame and thence between the guide pulley on said main frame and the guide adjacent thereto and thence to said spring drum, thus 65 providing an operative connection between said spring drum and platen carriage for exerting tension on said platen carriage for all positions of said platen carriage relative to said main frame.

In testimony whereof I have signed my 70 name to this specification on this 11th day of December, A. D. 1923.

OTTO A. HOKANSON.
